ABSTRACT: A folding bedframe including front and rear frame sections movable between a retracted vertical position wherein the bed frames are in generally parallel relationship, and an extended horizontal position wherein the bedframe sections are in generally coplanar relationship with the front bedframe section projected forwardly from the rear bedframe section. A first linkage mounts the rear frame section to an anchor means for swinging movement between a retracted vertical position and an extended horizontal position. Support for the rear frame section while in the horizontal position is provided by a second linkage pivotally connected to the anchor means for movement independently of the first linkage between a retracted position, and an extended position resting on the floor with the rear frame section engaged thereon. The front frame section is supported on the floor by means of a link which pivots into engagement on the floor when the front frame section is fully extended.

FOLDING BED LINKAGE

SUMMARY OF INVENTION

This invention generally pertains to folding beds and more specifically to a new and improved folding bedframe assembly and included linkage having particular utility in connection with beds which fold into an enclosure such as a cabinet, chest or wall although the present invention is not limited thereto.

One of the objects of the present invention is to provide a new and improved folding bedframe assembly including a new and improved linkage for supporting and moving the assembly between a retracted storage position and an extended use position. Included herein is the provision of such a linkage that has a relatively simple and compact construction and yet provides ample support for the bedframe and is moreover easily maneuverable between retracted and extended positions.

A further object of the present invention is to provide a folding bedframe assembly and associated linkage that may be compactly housed for storage in a cabinet or chest. Included herein is the provision of such a bedframe assembly that may be easily unfolded from the cabinet into a horizontal position for use and without tilting or upsetting the cabinet during unfolding.

In one embodiment of the invention, the above objects are achieved by means of a pair of generally rectangular front and rear bedframe sections which are interconnected by a linkage for movement between a retracted parallel position and an extended use position wherein the front bedframe section projects forwardly from the rear bedframe section in generally coplanar relationship. The rear bedframe section is mounted by means of a linkage to a fixed support or anchor means for movement between a vertical, retracted position and an extended, horizontal position.

Supporting the rear bedframe section when in the horizontal position is a main support linkage which is pivotally connected to the stationary support or anchor means for movement between a retracted position and an extended position underlying and supporting the rear bedframe section. The main support linkage is separate from the linkage which mounts the rear bedframe section to the anchor means. In unfolding the assembly, the main support linkage is first unfolded into the extended position and then the rear bedframe section is unfolded into horizontal position resting on the main support linkage with the front frame section still in retracted parallel position but overlying the rear frame section. The front frame section is then unfolded relative to the rear section into horizontal position forwardly of and in coplanar relationship with the bed rear-bed rear-frame section. This automatically unfolds a front support leg pivoted to the front frame section until the front support leg contacts the floor. Pivoting of the front support leg is obtained by an actuating link interconnecting the front support leg and the linkage which interconnects the front and rear frame sections. To retract the assembly the above steps are reversed.

Other objects and advantages will become apparent from the more detailed description taken in conjunction with the attached drawings in which:

FIG. 1 is a side elevational view of a bedframe assembly embodying the present invention shown in fully folded or retracted position in an enclosure which is shown in cross section;

FIG. 2 is a view generally similar to FIG. 1 but with a main support linkage included in the assembly, shown in a partially unfolded position projecting out of the enclosure;

FIG. 3 is a view generally similar to FIG. 2 but with the main support linkage in the fully unfolded or extended position wherein it rests on the floor;

FIG. 4 is a view generally similar to FIG. 3 but with bedframe sections included in the assembly shown in a partly extended position projecting out of the enclosure;

FIG. 5 is a view generally similar to FIG. 4 but with the bedframe sections shown in a further extended position, resting on the main support linkage;

FIG. 6 is a view generally similar to FIG. 5 but illustrating further unfolding of the bedframe sections relative to each other towards a fully extended coplanar position, and the enclosure and portions of the main support linkage being omitted;

FIG. 7 is a view generally similar to FIG. 6 but with the bedframe sections in the fully unfolded or extended position; and

FIG. 8 is a fragmental, perspective view of the bedframe assembly when in the fully extended or unfolded position and with one of the bedframe sections omitted.

DETAILED DESCRIPTION

15 Referring to the drawings in detail, there is shown for purposes of illustration only, a bedframe assembly embodying the present invention including front and rear bedframe sections generally designated 10 and 12 which are movable between a fully folded or retracted position shown in FIG. 1, and a fully extended or unfolded position shown in FIG. 7. Bedframe sections 10 and 12 per se may have a conventional rectangular construction formed by tubular steel side members 14 interconnected by tubular steel end members 16 and 18 illustrated in FIG. 8. A conventional mattress designated 20 is supported on the bedframes by means of a conventional wire spring (not shown) secured to the bedframe sections. Typical mattress stops 22 may be fixed to the ends of the bedframe sections as illustrated in FIGS. 2 and 8.

20 Although not limited thereto, the assembly is particularly suited for storage in the retracted position in an associated enclosure such as a chest, cabinet, closet or other similar structure generally designated 24 in the drawings. In the specific form shown, the enclosure 24 includes a flat top panel 26, vertical parallel side panels 28, and a rear panel 30 which define a space dimensioned to receive the bedframe assembly in the fully folded position as indicated in FIG. 1. Movement of the assembly into and out of the enclosure is through an opening designated 32 in the front wall of the enclosure. Doors or other suitable closures (not shown) movable into opening 32 may be provided to conceal the bedframe assembly when in the fully retracted position in the enclosure.

ANCHOR MEMBERS

25 In the preferred embodiment, the assembly is anchored at one end to the enclosure side panels 28 by two pairs of anchor members generally designated 34 and 36. Anchor members 34 and 36 may be formed by elongated steel bars, with one pair of anchor members being fixed to one side panel 28 such as with screws 38 and the other pair similarly fixed to the other side panel 28. In the specific embodiment, anchor bar 34 includes a lower portion 40 and an upper portion 42 extending at an obtuse angle of approximately 145° with respect to the lower portion. The other anchor bar 36 similarly includes lower and upper portions 44 and 46, however the angular interrelationship in this instance is approximately 100°.

30 The relative position between the anchor bars when fixed to side panel 28 is clearly shown in the drawings. The lower extremities of anchor bars 34, 36 engage the floor and this automatically positions them at the proper elevation along side panels 28. However, anchor bars 34, 36 need not be positively attached to the side panels 28 but instead may be freestanding. In this instance, anchor bars 34, 36 will be fixed against movement relative to each other by pivot pins 48, 50 which connect the anchor bars at their points of intersection.

35 Pivots connected to the anchor bars are what will be termed a "main support linkage" generally designated 60 and a "bedframe linkage" generally designated 62. Although the main support linkage 60 and bedframe linkage 62 at one side of the assembly will be described below, it will be understood that the other side of the assembly will have an identical main support linkage and bedframe linkage which will be connected to the adjacent pair of anchor members 34, 36.

MAIN SUPPORT LINKAGE

Main support linkage 62 includes an elongated generally rectilinear main support link 64 having one end pivotally connected by pivot 66 to anchor bar 36 just below the bite section 52 of the latter for movement between a fully retracted or folded vertical position in the enclosure (see FIG. 1) and a fully extended or unfolded position projecting outwardly of the enclosure (see FIGS. 3 and 5). Main support link 64 thus provides a main support leg, the free end 68 of which is free to engage the floor when in the fully extended position.

In the extended horizontal position, rear bedframe section 12 is supported on main support linkage 60 with the weight being transmitted to the floor through main support link 64. This is accomplished by means of an "auxiliary support link" generally designated 70 having one end pivotally connected by pivot 72 to an intermediate portion of main support link 64 and an opposite end fixed to a crossbar 74 which extends across the assembly to receive rear bedframe section 12 as shown in FIGS. 5 and 8. It will be understood that crossbar 74 extends between and is fixed to the upper ends of auxiliary support links 70 at opposite ends of the assembly. If desired resilient bumper members 76 may be fixed to the opposite side members 14 of rear bedframe section 12 to be engageable on the crossbar 74 as shown in FIG. 5. In addition, a depending arm 78 may be fixed to the underside of side members 14 to hook over crossbar 74 as shown in FIG. 5.

In order to lock auxiliary support link 70 in the extended operative position wherein it supports the bedframe section in horizontal position as shown in FIG. 5, a locking link 80 is pivotally connected between the anchor bars and auxiliary link 70. One end of locking link 80 is connected by pivot 50 to anchor bars 34, 36 while the opposite end is connected by pivot 82 to an intermediate portion of auxiliary support link 70. The location of pivot 82 and the shape of auxiliary link 70 is designed so that locking link 80 may be moved into retracted vertical position in the enclosure along with main support link 64 without jamming or interference as a result of auxiliary support link which is also movable into the enclosure. To this end in the shown embodiment, auxiliary support link 70 is formed in two parts 71 and 73 which extend at an angle of approximately 135° with respect to each other; and pivot 82 is located intermediate the ends of upper part 73. The angular shape of auxiliary support link 70 also allows its upper part 73 to extend upwardly sufficiently to permit crossbar 74 to engage the underside of rear bedframe section 12.

To enhance stability of main support linkage 60 as well as to insure that the main linkage at the opposite sides of the assembly will act together in unison during folding and unfolding, a crossbar 84 is fixed between main support legs 64 of each linkage in the position illustrated in the drawings. Crossbar 84 also provides a stop for movement of link 70 relative to main support 64 when the latter has come to rest on the floor at the same time pivots 50, 72 and 82 come in line with each other, which condition allows 70 to continue movement about pivot 72 until stopped by crossbar 84.

To unfold main support linkage 60 from the retracted position shown in FIG. 1 to the extended position shown in FIG. 5, cross tube 84 is grasped and pulled outwardly and downwardly away from the enclosure which will cause main support leg 64 to pivot in a clockwise direction (as viewed in the drawings) about pivot 66. Locking link 80 will also pivot clockwise about its pivot 50 because of its connection to main support link 64 through auxiliary support link 70. Locking link 80 however, during this unfolding, will move along a flatter arc than main support link 64 and thus cause auxiliary support link 70 to unfold about its pivot 72 counterclockwise relative to main support link 64 as illustrated in FIG. 2. When main support leg 64 engages the floor, locking link 80 together with crossbar 84 will have positioned (see FIG. 3) auxiliary support link 70 with crossbar 74 at the proper elevation for receiving rear bedframe section 12. It will be noted that pivot 82 lies on two

10

5 different arcs of movement, and when pivots 50, 72 and 82 are in line, the linkage sets up a condition of rigid triangulation involving pivotal triangle 50, 72 and 66 thus preventing relative movement between main support link 64 and anchor bar 36 thus preventing tilting of cabinet. Then, when the bedframe is extended to rest upon 74 the weight of the bedframe is transferred through auxiliary link 70 to crossbar 84 to main support link 64 and finally to the floor.

BEDFRAME LINKAGE

After main support linkage 60 is extended into the horizontal position shown in FIG. 3, bedframe sections 10, 12 are moved out of the enclosure and on to main support linkage 60 by means of bedframe linkage 62.

20 Bedframe linkage 62 is separate from main support linkage 60 and includes a pair of rectilinear links 90 and 92 pivotally connected by pivots 48 and 94 to the anchor bars at locations indicated in the drawings (see FIG. 5). Link 92 is pivotally connected to rear bedframe section 12 by pivot 96 which is received in side member 14 of the rear bedframe section. Link 90 is pivotally connected to the rear bedframe 12 by means of a short link 98 having a generally L shape one end of which is connected by pivot 96 to the rear bedframe section while the other end projects from the rear bedframe section and is pivotally connected by pivot 100 to link 90. However short link 98 is fixed against relative movement with respect to rear bedframe section 12 by means of a pin 102 received in side member 14.

30 It will thus be seen that links 90, 92 form swing arms for rear bedframe section 12 for projecting the latter out of the enclosure relative to the anchor bars. In addition, bedframe section 12 is free to pivot about pivots 96 and 100 relative to links 90 and 92 to enable the bedframe section 12 to move between the vertical retracted position shown in FIG. 1 and the horizontal extended position shown in FIG. 5.

35 In their retracted positions, links 90, 92 extend downwardly at an angle from their pivotal connections 48, 94 as shown in FIGS. 1 and 2. In their extended positions, links 90, 92 form with anchor bar 42 and side member 14 of the bedframe section, a generally right triangle as indicated in FIGS. 5 and 8. It will be seen that when in the horizontal position shown in FIG. 5, bedframe sections 10, 12 are supported relative the anchor bars by means of links 90, 92 in addition to being supported on main linkage 60. Moreover in this position of the assembly, two trusses are formed in effect by main support linkage 60 and bedframe linkage 62 with side member 14 of rear frame section 12 forming a tension member for both of the trusses.

40 To move the bedframe sections from the retracted vertical position shown in FIG. 1 to the extended position shown in FIG. 5, crossbar 18 is merely pulled forwardly away from the enclosure which causes links 90, 92 to swing counterclockwise about their pivots 48, 94 while at the same time causing bedframe section 12 to pivot clockwise relative to the links 90, 92 as illustrated in FIG. 4. Continued pulling of crossbar 18 in the forward direction will eventually cause bumper 76 to engage on crossbar 74 with arm 78 hooked over the latter.

45 After the assembly is moved into the position shown in FIG. 5, the next unfolding step is to move front mattress section 10 relative to rear section 12 into the fully extended position shown in FIG. 7.

50 This is accomplished through a pair of "crisscross" links 110, 112 which extend rectilinearly across each other and are pivotally connected at their opposite ends with respect to both bedframe sections. Link 110 is pivotally connected to side member 14 of bedframe sections 10 and 12 by means of pivots 114 and 116. The position of pivot 116 in the shown embodiment is determined by means of an arm 118 rigidly fixed to front section 10 to receive pivot 116. The other link 112 is pivotally connected to side member 14 of frame sections 10, 12 by pivots 120, 122. When the bedframe sections are in the vertical retracted position shown in FIG. 1, links 110, 112 serve to maintain the bedframes in parallel relationship. The

same parallel relationship of the bedframe sections is also maintained by links 110, 112 when the bedframe sections are moved to the position shown in FIG. 5.

In order to extend front bedframe section 10 from its position shown in FIG. 5, it is swung upwardly relative to links 110, 112 and moved forwardly relative to rear bedframe section 12 with links 110, 112 allowing such movement as indicated in FIG. 6, until the front bedframe section is positioned horizontally and coplanar with rear frame section 12 as indicated in FIG. 7. Links 110, 112 are made of sufficient length and their pivots 116, 122 placed in proper spaced positions along side member 14 of front bedframe section 10 to obtain the foregoing movement of front bedframe section 10.

To support front bed section 10 above the floor in coplanar position with rear bedframe section 12, a foldable support leg 130 is pivotally connected by pivot 132 to an intermediate portion of side member 14 of front bedframe section 10. Front support leg 130 is actuated by a link 134 from a retracted position generally adjacent the plane of bedframe section 10 into an extended position in engagement with the floor upon movement of the front bedframe section 10 into the extended position. One end of link 134 is pivotally connected by pivot 136 to an intermediate portion of front support leg 130 while the other end is pivotally connected by pivot 138 to an intermediate portion of link 110.

When link 110 moves in the clockwise direction upon unfolding of front bedframe section 10, link 134 will be drawn downwardly to pivot and unfold front support leg 130 relative to the front bedframe section. Link 134 also serves to lock front support leg 130 in the extended position engaged on the floor. In the extended horizontal position front bedframe section 10 is thus supported by means of leg 130 and also by means of its connection through crisscross links 110 and 112 to rear mattress section 12. A crossbar 140 is preferably provided between front support legs 130 of each linkage for stability and also to insure they move in unison during folding and unfolding.

Crisscross links 110 and 112 coupled with leg 130 and control link 134 also serve to lock sections 10 and 12 in their closed (parallel) position, which is required because of the varying resistance to compression afforded by mattresses. When pivots 136, 132 and 138 are operated into alignment with each other, a condition of rigid triangulation is set up involving pivotal triangle 132, 138 and 116 thus preventing relative movement between 110 and 10 and consequently preventing operation of the crisscross linkage. Crossmember 140 in this instance serves as a stop to prevent further movement of leg 130 relative to section 10.

OPERATION

To summarize unfolding of the complete assembly from the retracted position in the enclosure shown in FIG. 1, crossbar 84 of main support linkage 60 is pulled forwardly and downwardly to cause clockwise movements of main support leg 64 and auxiliary link 70 about their pivots 66 and 50 until main support leg 64 engages the floor as shown in FIG. 3. During this movement, bedframe sections 10 and 12 remain in their retracted parallel vertical positions in the enclosure. End member 18 of rear bedframe section 12 is then pulled forwardly to swing the bedframe sections out of the enclosure by means of links 90 and 92 which pivot in a counterclockwise direction from the retracted position shown in FIG. 3. Upon continued movement, the bedframe sections pivot downwardly relative to links 90 and 92 until rear bedframe section 12 is engaged upon crossbar 74 of the main support linkage. At this point, front bedframe section 10 is still parallel to rear bedframe section 12 but in an overlying position as indicated in FIG. 5. The next and final step is to swing front frame section 10 upwardly and forwardly until the front support leg 130 engages the floor as shown in FIG. 7.

To fold the assembly into the enclosure, the above steps are essentially reversed. After the assembly is folded into the en-

closure, crossbar 84 of main support linkage 60 serves to hold the bedframe sections in the vertical retracted position.

Modifications and adaptations of the present invention readily apparent from the foregoing description and associated drawings, although not specifically mentioned herein, will nevertheless be included within the scope of the present invention as indicated in the appended claims.

I claim:

1. Linkage for a section of a folding bedframe having an associated anchor means; the linkage comprising in combination, support linkage means adapted to be connected to said anchor means for movement between a retracted position and an extended horizontal position, and a bedframe linkage means adapted to be connected at one end to said bedframe and at the other end to said anchor means to mount the bedframe for movement between a retracted position and an extended horizontal position overlying and engaged on said support linkage means, said support linkage means and said bedframe linkage means being separate from each other and arranged such that said support linkage means is first movable from the retracted to the extended position and then the bedframe linkage means is movable from the retracted to the extended position overlying the support linkage means.
2. The linkage defined in claim 1 wherein said bedframe linkage means includes two links adapted to be connected at their opposite ends to said bedframe and said anchor means.
3. The linkage defined in claim 2 wherein said bedframe linkage means further includes a third link having one end connected to said bedframe and an opposite end connected to one of said two links.
4. The linkage defined in claim 2 wherein said support linkage means includes a main support leg having one end adapted to be connected to said anchor means and another end adapted to engage the floor when the support linkage means is in the extended position, an auxiliary support link having one end connected with respect to an intermediate portion of said main support leg and an opposite end adapted to engage below the bedframe when the bedframe is in the horizontal position, and a locking link having one end connected to an intermediate portion of said auxiliary support link and an opposite end adapted to be connected to the anchor means.
5. The linkage defined in claim 1 wherein said support linkage means includes a main support leg having one end adapted to be connected to said anchor means and another end adapted to engage the floor when the support linkage is in the extended position, an auxiliary support link having one end connected with respect to an intermediate portion of said main support leg and another end adapted to engage below the bedframe when the bedframe and main support linkage means are in the extended positions, and a locking link having one end connected to an intermediate portion of said auxiliary support link and another end adapted to be connected to said anchor means.
6. In combination with the structure defined in claim 1, a second bedframe section, and connecting linkage means interconnecting said second bedframe section and said first bedframe section for movement between a retracted position wherein said first and second bedframe sections are in generally parallel relationship and a fully extended position wherein said bedframe sections are in generally coplanar relationship with said second bedframe section projected forwardly from said first bedframe section.
7. The combination defined in claim 6 wherein said interconnecting linkage means includes a pair of links having their opposite ends pivotally connected to said bedframe sections such that when the bedframe sections are in parallel relationship, said pair of links cross each other and maintain said bedframe sections against movement towards each other.
8. The combination defined in claim 7 further including a second support leg having one end pivotally connected to said second bedframe section for movement between a retracted position adjacent the plane of said second bedframe section and an extended position projecting downwardly from said

second bedframe section into engagement with the floor, and an actuating link having one end pivotally connected to an intermediate portion of said second support leg and an opposite end pivotally connected to one of said pair of links so as to be operated by the latter upon movement of the second bedframe section into fully extended position to thereby actuate said second support leg into extended position in engagement with the floor.

9. In combination with the structure defined in claim 4, a second bedframe section and interconnecting linkage means connected between said first and second bedframe sections to mount the second bedframe section for movement between a retracted position generally in parallel relationship with said first bedframe section and an extended position forwardly of said first bedframe section and in generally coplanar relationship therewith.

10. The combination defined in claim 9 wherein said bedframe linkage means further includes a third link having one end pivotally connected to said first bedframe section and an opposite end pivotally connected with respect to one of said two bedframe links.

11. In combination with an enclosure having an opening therein, a folding bed assembly including anchor means located within said enclosure, a first bedframe, linkage means interconnecting the bedframe to said anchor means for movement of the bedframe between a retracted position in said enclosure and an extended horizontal position projecting through said opening outwardly of said enclosure, and a bedframe support means separate from said linkage means and being connected to said anchor means for movement between a retracted position within said enclosure and an extended position extending through said opening below said bedframe and with a portion of the bedframe resting on said support means.

12. The combination defined in claim 11 further including a second bedframe and interconnecting linkage means connecting said second bedframe to said first bedframe for movement

between a retracted position parallel with said first bedframe and an extended position forwardly of said first bedframe and in generally coplanar relationship therewith.

13. The combination defined in claim 11 wherein said linkage means includes a pair of links having their opposite ends pivotally connected to said anchor means and said bedframe respectively, and wherein said support means includes a leg having one end pivotally connected to said anchor means and an opposite end adapted to engage the floor when the bedframe is in horizontal position, an auxiliary support link having one end pivotally connected to an intermediate portion of said leg and an opposite end adapted to engage below said bedframe when the bedframe is in horizontal position, and a locking link having one end pivotally connected to an intermediate portion of said auxiliary support link and an opposite end pivotally connected with respect to said anchor means.

14. The combination defined in claim 13 wherein said first bedframe linkage means includes a third link having one end pivotally connected to one of said pair of links and an opposite end connected to said first bedframe.

15. A folding bedframe combination including; a bedframe, mounting linkage means connected to the bedframe and adapted to be connected to an anchor for mounting the bedframe for movement between a retracted position and an extended position in generally horizontal plane, and a support linkage means separate from said mounting linkage means and adapted to be connected to the anchor for movement between a retracted position and an extended position for supporting said bedframe in generally horizontal position.

16. The combination defined in claim 15 further including an anchor means, said mounting linkage means being pivotally connected to said anchor means to move said bedframe between a vertical retracted position and said horizontal extended position, and said support linkage means being pivotally connected to said anchor means to be movable between a vertical retracted position and said horizontal extended position.
